UNITED STATES PATENT OFFICE.

JOHN HENRY SMITH, OF LA GARENNE-COLOMBES, FRANCE.

PROCESS OF INTRODUCING WATER-INSOLUBLE OILS INTO EMULSIONS OR WATER-SOLUBLE BODIES.

1,096,465.

Specification of Letters Patent.

Patented May 12, 1914.

No Drawing.

Application filed September 28, 1912. Serial No. 722,947.

To all whom it may concern:

Be it known that I, JOHN HENRY SMITH, a citizen of Great Britain, residing at La Garenne-Colombes, France, have invented 5 a certain new and useful Improvement in Processes of Introducing Water-Insoluble Oils into Emulsions or Water-Soluble Bodies, of which the following is a specification.

10 It is often desirable to bring ethereal oils into intimate combination with bodies soluble in water, either on the score of economy or of other advantages accruing therefrom.

In practising the bleach-out process of 15 color photography, it would be of great advantage to employ the ethereal oils, on account of their favorable properties as sensitizers, in combination with gelatin and such like excellent water-soluble mediums.

20 of support. Hitherto, however, this has not been practised on account of the insolubility of these oils in water. I have found that many of these ethereal oils may be brought into intimate combination with gel-

25 atin either in a state of solution or in the form of a very fine emulsion by mixing with water-soluble oils such as Turkey red oil in watery solution and drying the resulting mass preferably spread out in a thin layer.

30 It is best to mix the ethereal oil first with

the water-soluble oil and then add to the gelatin solution or emulsion; but the water-soluble oil may be added first to the gelatin solution and the ethereal oil afterward.

What I desire to secure by Letters Patent 35 is:

1. The process for the introduction of water insoluble oils into emulsions or water soluble bodies, which consists in incorporating water insoluble oils and water soluble 40 oils with the emulsion or water soluble body.

2. The process for the introduction of water insoluble oils into emulsions or water soluble bodies, which consists in mixing the water insoluble oil with a water soluble oil, 45 and incorporating the mixture in the emulsion or the aqueous solution of the soluble bodies.

3. The process for the introduction of water insoluble oils into emulsions or water 50 soluble bodies, which consists in mixing the water insoluble oil with a water soluble oil, incorporating the mixture in the emulsion or the aqueous solution of the soluble bodies; and spreading the mass so obtained for the 55 purpose of drying.

JOHN HENRY SMITH.
